UNITED STATES PATENT OFFICE.

WILLIAM ZOERB, OF BOSTON, MASSACHUSETTS.

DESIGN FOR AN EYEGLASS-CASE.

SPECIFICATION forming part of Design No. 34,056, dated February 12, 1901.

Application filed November 13, 1900. Serial No. 36,415. Term of patent 14 years.

To all whom it may concern:

Be it known that I, WILLIAM ZOERB, a citizen of the United States, residing in Boston, county of Suffolk, and State of Massachusetts, have invented and produced a new and original Design for an Eyeglass-Case, of which the following is a specification, reference being made to the accompanying drawings, forming a part thereof.

Figure 1 is a plan view of my design for an eyeglass-case; Fig. 2, a front edge view, and Fig. 3 an end view.

As shown in the drawings, the leading or material features of my design for an eyeglass-case consist in the body *d*, the lid *c*, having its front edge narrowed at each end to ex-

pose the body of the case, the projection *b*, curved downwardly and around the front edge of the case, and the outwardly-projecting and slightly upwardly turned lip *a* at one side of the projection *b*.

I claim—

The design for an eyeglass-case, as herein shown and described.

In testimony whereof I have signed my name to this specification in the presence of two subscribing witnesses.

WILLIAM ZOERB.

Witnesses:

B. J. NOYES,
H. B. DAVIS.
